UNITED STATES PATENT OFFICE.

THOMAS J. LEWIS, OF NEW YORK, N. Y.

DESIGN FOR A BATH-SALT BOTTLE.

Application filed December 23, 1927. Serial No. 24,600. Term of patent 14 years.

To all whom it may concern:

Be it known that I, THOMAS J. LEWIS, a citizen of the United States, residing at New York, in the county of New York and State of New York, have invented a new, original, and ornamental Design for a Bath-Salt Bottle, of which the following is a specification, reference being had to the accompanying drawing, forming part thereof, and in which:

I claim:

The ornamental design for a bath salt bottle, as shown.

THOMAS J. LEWIS.
